WATER CLOSET

Clarence H. Johnson, Chicago, Ill., assignor to
 Pullman-Standard Car Manufacturing Company, Chicago, Ill., a corporation of Delaware

Application August 12, 1939, Serial No. 289,848

14 Claims. (Cl. 4-85)

This invention relates to water closets for railway cars and has for its primary object the provision of a lightweight closet structure and operating mechanism.

The invention involves the use of an upper dumping pan and a bottom closure member with operating mechanism therefor designed to effect full closing of the bottom closure member before initiating the dumping action of the upper pan and the return movements of such members in reverse sequence, whereby the initial opening movement of the bottom closure member is delayed until the upper dumping pan is restored to fully closed, normal position.

The invention also contemplates the restoration of the flushing mechanism for the water closet to its normal non-flushing condition in the event that the upper pan is prevented from returning to normal, closed position, or the bottom closure member either to normally open or closed position, or both members affected simultaneously by an obstruction in the closet, thereby to prevent draining of the water supply tank.

The principal object of the invention is to provide a compact operating mechanism requiring less space for its full range of action and having lost motion mechanism between the upper pan and the bottom closure member adapted to afford sequential operation of such members in the order desired without the use of weights and having other lost motion means normally supporting the upper pan in closed position but adapted to afford full opening of such pan.

Specifically, the invention contemplates the provision of torsional spring devices adapted, one of them, normally to maintain the upper pan in closed position and the other to permit opening the upper pan after the bottom closure member has been actuated and providing, respectively, lost motion means whereby the operation of the upper pan might be obstructed without adversely affecting the mechanism and lost motion means adapted to absorb the continued movement of the mechanism necessary to dump the upper pan.

The invention has for its further and important object the provision of a water closet for railway cars preferably constructed of lightweight stainless steel, or other suitable non-corroding metal, pressed or drawn to the required shapes and suitably welded.

The foregoing and other and more specific objects of the invention are attained by the mechanism illustrated in the accompanying drawings, in which—

Fig. 1 is a plan view of the hopper and oper-

ating mechanism with parts broken away better to show the flushing valve operating arrangement;

Fig. 2 is a side elevational view of the hopper with the operating mechanism in normal position with the upper pan closed and the bottom closure member open;

Fig. 3 is a similar view of the hopper with the mechanism operated to a point where both the upper pan and the bottom closure member are disposed in fully closed position;

Fig. 4 is still another side elevational view of the hopper with the mechanism further operated to its final extreme position of movement with the upper pan in the fully open or dumping position and the bottom closure member still fully closed and from which position the parts then assume the position illustrated in Fig. 2, in which position the lower chamber is permitted to empty;

Fig. 5 is a vertical sectional view through the center of the hopper taken on the line 5—5 of Fig. 1 with the operating parts in normal position and illustrating the hopper construction;

Fig. 6 is a vertical, transverse sectional view through the center of the hopper, taken on the line 6—6 of Fig. 2, with the parts in normal position and further illustrating the hopper construction;

Fig. 7 is an enlarged, fragmentary, sectional view of the upper pan shaft mounting and mechanism and the bottom closure member mounting;

Fig. 8 is a sectional view through the upper pan shaft taken on the line 8—8 of Fig. 7 and showing the spiral spring arrangement for providing a lost motion connection between the upper pan and the bottom closure member;

Fig. 9 is a sectional view through the upper pan shaft taken on the line 9—9 of Fig. 7 and showing the spiral spring arrangement for urging the upper pan toward closed position;

Fig. 10 is a detail, perspective view of the member on the upper pan shaft for co-operating with the lost motion mechanism;

Figs. 11 and 12 are detail, perspective views of the parts of the lost motion mechanism which house the spiral spring;

Fig. 13 is a fragmentary, broken-away, perspective view of the upper pan and bottom closure member with the operating mechanism;

Fig. 14 is a similar view of a modified form of the invention in which a spiral spring arrangement is also used on the bottom closure member shaft; and

Figs. 15 and 16 are detail side-elevational and

cross-sectional views, respectively, of the modified arrangement.

In the drawings, 10 represents a water closet constructed in accordance with the invention and including the base member 11 having outwardly extending bottom flange 12 which may be reinforced, if desired, by ring member 13 to prevent distortion thereof when secured to uneven supporting surfaces. The base tapers upwardly, as at 14, to a point intermediate the height of the water closet where it is provided with a vertically disposed flange 15 continuous about the perimeter and having a horizontal top surface. A chute member 17 is disposed within the base member 11 and secured at the position of the vertical flange 15 by welding. The chute is tapered downwardly to a bottom opening and is provided with a recess 18 in the rearmost wall for a purpose hereinafter to appear. The flange 15, with the top edge of the chute 17, provides a throat into which housing member 16 is received and adapted to be secured by welding—one series of continuous spot welds securing the three thicknesses of metal comprising the flange 15, the chute 17 and the housing member 16. Above the point of attachment to the flange 15 and the chute member, the rear wall 19 of the member 16 extends substantially vertically, while the respective side walls 20 flare outwardly above that point, and the front wall 21 is also flared, to a substantially greater degree, to provide an extended front. The side walls 20 are each provided with a recess 22 having a horizontally disposed top surface perforated at 23 for a purpose hereinafter to be described. At the top, the housing member 16 is provided with an outwardly extending flange 24 continuous about the upper edge and disposed on a horizontal plane to provide a seat. The housing member 16 and the base member 11, together with the chute 17, all integrally secured together, comprise the stand portion of the water closet. The base and chute members are each of them formed from a single, integral piece of metal drawn to the desired shape, but the housing member is developed from a single blank of metal, of the desired contour, having a vertically disposed, interlocking, welded seam in the rear wall and pressed to the required shape.

The horizontal seat afforded by the top flange 24 on the housing member 16 is embraced by a sealing gasket 25 which may be of rubber, if desired, or any other suitable material. Seated upon this gasket is the bowl 26 of the water closet having the horizontally disposed shelf portion 27 complementary to and supported from the seat afforded on the stand. The bowl is provided with an extended front corresponding to that of the stand and, from the shelf portion 27 inside the stand, tapers down to a discharge opening emptying into the chute 17. From the shelf 27 upwardly, the bowl extends vertically a short distance, as at 28, and then is provided with an outwardly extending flange 29 for attachment thereto of the rim 30 by welding. The rim is provided with the elongated opening 31 having curved edges, as at 32, and is provided with an overhanging portion 33 at the rear for the support of mechanism presently to be described. The rim 30 is provided with a rolled edge 34 afforded by rolling the metal about a wire filler or core. The rim is pressed to the desired shape, while the bowl proper 26 is drawn to the contour required to provide proper draining surfaces. At opposite sides, in positions complementing the 75

recesses 22 in the respective side walls of the stand, the bowl is provided with fabricated projections 35 secured to the sides of the bowl by welding and having threaded portions adapted to receive removable stud bolts 36 entered through the openings 23 in the top surface of the recess 22 securely to retain the bowl 26 in proper sealing relation to the stand.

Flushing mechanism 45 is provided for the water closet and is supported wholly from the bowl and rim structure, as best shown in Figs. 1 and 5. A supporting bracket 46 is secured to the overhanging rim structure 33 by means of bolts 47 and is formed with depending flanges 48 disposed at opposite sides to provide spaced bearings for the reception of the hollow operating shaft 49. An operating lever 50 is pressed onto one end of the shaft 49 and secured by a pin 39 and bears against one side of one of the depending flanges 48, thereby to prevent displacement of the shaft with respect to the flange in one direction. A bifurcated actuating cam 51 is securely anchored on the operating shaft at the opposite side of the depending flange referred to by means of set screw 52 and serves to prevent movement of the shaft in the opposite direction, whereby axial displacement thereof is positively prevented. The bifurcated jaws of the cam 51 are adapted to engage the ball-shaped end 53 of bell-crank lever 54 which is pivoted on integral stud 55 depending from the underside of the supporting bracket 46 and the bifurcated arm 56 of which engages the operating plunger 57 of the flushing valve 58 to change the rotary motion of the cam 51 into a horizontal thrust on the valve plunger when the operating lever 50 is actuated. The free end of the plunger 57 finds bearing in a flanged bracket member 59 secured to the flushing valve 58 by means of cap screws taking the studs 60 integral therewith. The bifurcated arm 56 of the bell-crank 54 engages bearing block 61 on the plunger 57 in order to actuate that member.

The flushing valve 58 is mounted from flange 63 depending from the rear of the supporting bracket 46 by means of securing nuts taking integral studs 64 on the valve body. The valve is connected to a source of water supply, at 65, and communicates with the interior of the closet bowl 26 by means of an intervening T-shaped member 66 secured to the bowl at 67 and to which the flushing valve is connected at 68. The T member 66 is provided with one spout 69 adapted to direct flushing water into the area of the rim of the bowl on the shelf 27 and another spout 70 adapted to direct water in the same direction into the bowl 26, whereby an effective whirling action of the water is set up thoroughly to flush the closet. A tray 71, supported at its free end from one of the studs 64 by means of the securing nut, extends beneath the flushing valve 58 to collect any moisture dripping therefrom and drains into the closet stand as at 72. The flushing mechanism is actuated coincidentally with the operation of operating mechanism for the upper dumping pan and bottom closure member, as hereinafter described, by means of treadle 74 fulcrumed intermediate its ends at 41 on fulcrum bracket 73—here shown as supported directly from the floor independently of the closet stand, but which, if desired, may be incorporated with the bottom flange reinforcing ring 13 as an integral portion thereof.

One end of the treadle 74 is pivotally connected at 42 with a strut 44 which, in turn, is

pivotedly connected at 43 to the flushing mechanism operating lever 50, whereby, upon depression of the foot-engaging portion of the treadle, causing an upward thrust on the strut 44, the shaft 49 will be rotated to cause the cam 51 to actuate the bell-crank 54, thereby to press the plunger 57 of the flushing valve and flush the closet. The location of the fulcrum 73 with respect to the ratio of the length of the lever 74 upon opposite sides thereof, together with the height of the fulcrum above the floor, will, of course, determine the length of travel of the operating parts; and bodily shifting of the fulcrum and treadle lever fore and aft, thereby increasing the angle of the strut 44, will determine the range of operation—all in accordance with requirements of the various flushing valves differing slightly in dimension and operation. A resilient bumper 40 is disposed on the underside of the treadle at the foot-engaging portion to prevent metallic contact with the floor or supporting surface and serves as a limit of movement for the operating mechanism. The treadle mechanism is used as a gauge in initially installing the arrangement. When it is desired to locate the fulcrum bracket 73, the strut 44 is secured to the valve operating lever 50 by the connection 43 and the treadle 74 then pivoted about the fulcrum 73 to a position with the bumper 40 contacting the floor. The bracket 73, with the lever 74, is then shifted to a position where the maximum range of operation of the particular flushing valve is obtained, and secured. By disconnecting the drip tray 71 and the connection 43, it will be seen that the entire flushing mechanism can be removed with the bowl 26, from which it is wholly supported, without disturbing any of the other mechanism.

An upper dumping pan 75 is provided which, in the normal position, is adapted to seal the discharge opening 80 from the closet bowl 26; and a bottom closure member 85 is provided which, in its closed position, is adapted to seal the bottom drain opening 90 from the chute 17. The upper pan is insulated, as at 76, the insulation being enclosed by outer shell 71. The dumping pan 75 is actuated by means of the hollow upper shaft 81 to which the pan is anchored by means of attaching bracket 78 through the medium of set screws 79. The shaft 81 is pivotally carried in spaced bearing members 82 and 83 disposed adjacent opposite ends thereof and separate from but fixedly secured in the respective side walls 20 of the closet stand immediately above the joinder of the base 11 with the chute 17 and housing member 16 by means of similar nuts 84 clamping the side walls between similar shoulders 86, on the respective bearings, and the nuts. The bearing 83 is provided with an outwardly disposed seat 87 upon which a flat spiral torsional spring 88 is mounted and the inner end of which is anchored thereto by flange 89 entered in slot 99. The outer end of the spring is connected by rebent flange 91, through slot 101, to the circumferential flange 92 of a disk 93 enclosing the spring and having integral hub 94 securely anchored to the shaft 81 by means of set screw 95 for rotation therewith. The tension on the spring 88 may readily be adjusted merely by winding up the spring by means of the member 93 to the desired degree before setting the screw 95. The amount of spring tension necessary is determined solely by the force required to counterbalance the dumping pan 75 in closed position. Thus, it will be seen that since the bearing 83

of which the spring seat 87 is an integral part is rigidly fixed the spring 88 will exert a force on the member 93 tending to rotate the shaft 81; and by the direction of the coils of the spring, it will be noted that this force is exerted to rotate the shaft in a direction to urge the dumping pan towards fully closed position against limit stop 96 where it is normally maintained.

Disc washer 97, seated against collar 98 on the bearing 83, encloses the inner side of the spring 88 and cooperates with the disk 93 and flange 92 to constitute a housing for the spring. The bottom closure member 85 is provided with spaced stub shafts 102 offset from the plane of such member, whereby the axis of operation is disposed above the floor line and the bottom member therebeneath and by means of which the member is pivotally mounted in spaced, similar bearing members 103 separate from but fixedly secured in the respective side walls of the base member 11 by means of similar nuts 104 clamping such side walls between shoulders 105, on the respective bearings, and the nuts. A counterweight 106 is securely anchored to the outer end of one of the stub shafts 102 by means of set screw 107 in a position tending to urge the bottom closure member 85 toward open position where it is normally held. A resilient bumper 108 is disposed on the underside of the counterweight to deaden the sound of operation and comes in contact with bottom flange 12 of the base 11 to limit the opening movement of the member 85. While the side walls of the housing 16 and the base 11, in which the shafts 81 and 102, respectively, are mounted, are disposed at an angle to such shafts, it will be noted, as best shown in Fig. 7, that such walls are provided with parallel portions at right angles to the axes of the respective shafts for attachment of the shaft bearing members 82, 83 and 103.

The operating mechanism for the dumping pan 75 and the bottom closure member 85 is designed for sequential operation of those members and coincidentally with the flushing operation, with the bottom closure member first coming fully closed against the chute opening 80 before the dumping pan begins to move away from its seat against stop 96 to expose the discharge opening 80. The bottom closure member 85 is operated directly from the treadle 74 through mechanism including the strut 44 and separately from the dumping pan 75. A slotted lever 120 is securely anchored on the outer end of one of the bottom closure member stub shafts 102 by means of a set screw 121 and provides an arm by means of which the bottom closure member may be actuated. A slot 122 is provided in the lever which is adapted to receive a projecting lug 123 on an operating lever 124 and provides a means of compensating for the relative movement between the two members as they traverse their respective arcuate paths about their axes. While the slot 122, as shown, is disposed in the lever 120 and the lug 123 on the lever 124, it will be understood that such arrangement might be reversed with the slot 122 in the lever 124 and the lug 123 disposed on the lever 120 without impairing the function or operation of the mechanism. Or, if desired, the slot 122 might be dispensed with altogether and a direct pivotal connection between the lever 124 and lug 123 substituted with a telescopic connection provided in the lever 124 to compensate for the displacement necessary in the arcuate movement.

The lever 124 is an assembly comprised of an operating disc 125 and the lever and are both mounted on a sleeve 126 and provided with an intervening torsional spring 127 anchored at opposite ends to each and acting therebetween to cause such members to operate in unison to actuate the slotted lever 120 to close the bottom closure member 85. The lever 124 is provided with a hollow cylindrical portion 128 of which the lever is an integral part and having a hub 129 for mounting upon the sleeve 126. The torsional spring 127 is disposed within the hollow cylindrical portion 128 and anchored at its outer end to the perimeter thereof by means of rebent flange 131 engageable through slot 130. The operating disc 125 is provided with a hub 132 seated on the sleeve 126 and extending within the hollow cylindrical portion 128 and to which the inner end of the torsional spring 127 is anchored by means of flange 134 entered within slot 133. The operating disc 125 is provided with an integral, laterally extending lug 135 projecting into the path of movement of the lever 124 and against which such lever bears under the influence of spring 127. The lever 124, operating disc 125 and spring 127 may be assembled on the sleeve 126 as a unit prior to mounting upon the shaft 81, and the spring may be adjusted to any desired degree of tension merely by relative rotation of the opposing parts in a direction to wind up the spring and thereby to cause the lever 124, in operation, to move in unison with the operating disc 125 to actuate the bottom closure member 85. The adjustment is maintained by the engagement of the lever 124 with the lug 135. The sleeve 126 is mounted upon the shaft 81, freely, for relative rotation with respect thereto; and the lever 124 and the disc 125 are mounted upon the sleeve for relative rotation therebetween, whereby the whole mechanism is disposed in floating relation to the shaft 81 which merely acts as the axis for the pivotal operation thereof. The lever mechanism 124 and 125, with the spring 127 and including the sleeve 126, is held in assembled relation upon the shaft 81 by means of a collar member 144 having an annular flange 145 embracing the outer hub portion 146 of the disc 125 and anchored on the outer end of the shaft 81 by means of set screw 142. The mechanism is confined between the collar 144 and the collar 86 on the shaft bearing 82, whereby the lever 124 operates in a plane for co-operation with the bottom closure member operating arm 120 by means of the projecting lug 123.

The disc 125 is operated by the treadle 74 and for this purpose is provided with an integral, laterally projecting lug 136 by means of which the disc is rotated through a connecting link 137 extending between the lug 136, to which it is secured by washer 138 and fastening means 139, and the connection 43 to the flushing mechanism operating lever 50 which is operated directly by the strut 44 from the treadle 74, whereby the link 137 provides a means of operating the disc 125 coincidentally with the flushing mechanism upon depression of the treadle 74. The connecting link, where it associates with the lug 136 on the disc 125, is provided with a slot 143 for a purpose hereinafter to appear. Thus, it will be seen that upon actuation of the treadle the initial movement causes the bottom closure member 85 immediately to assume its fully closed position in sealing relation to the opening 90 from the chute 17. The immediate response of the bottom closure member to the flushing ac-

tion occurs prior to any movement whatever of the upper dumping pan 75 and is necessary to prevent the possibility of a draft from the opening 90 through the discharge opening 80 as 5 would occur if the upper pan opened before or during the raising movement of the bottom closure member; and, during this initial movement, the lever 124 and disc 125 move in unison as though they were a single integral member. The 10 disc 125 is designed also to operate the dumping pan 75 and, for this purpose, is provided with a laterally extending stud 140 engageable, after the bottom closure member 85 has reached its sealing position with respect to opening 90 and 15 upon continued movement of the operating parts, with a crank arm 141 formed integrally with the collar 144 anchored to the shaft 81 by means of set screw 142, thereby to rotate that shaft and dump the pan 75 which empties into the chute 17 as the pan enters the recess 18 provided in 20 the rear wall of the chute for that purpose.

During the continued movement of the operating parts necessary to operate the dumping pan after the bottom closure member 85 reaches 25 its final position, the operating lever 124 for the bottom closure member remains fixed in the final position of movement to close the member 85, while the operating disc 125 continues to rotate relatively with respect to the cylindrical portion 30 128 under the influence of the connection 137 to the operating mechanism and against the increasing tension of the torsional spring 127 as the lug 135 moves away from the lever 124, at 35 which time the spring is wound more tightly during such relative rotation of the parts and, upon release of the operating pressure, unwinds to the point where the lug 135 again contacts the lever 124.

The sequential operation of the mechanism in 40 its various progressive positions assumed during the flushing period is best depicted in Figs. 2, 3 and 4. In Fig. 2, all of the parts, including the flushing mechanism, are shown in their normal position of rest with the dumping pan 75 closed and the bottom closure member 85 open. The lever 124 is seated against the lug 135 and the stud 140 is spaced from the crank arm 141. When it is desired to flush the closet, it is necessary merely to step upon the treadle 74 which 45 pivots about the fulcrum 13 to exert an upward thrust on the strut 44 and thereby actuate the lever 50 to operate the flushing valve 58 by means of the cam 51 and bell-crank 56. The pan 75 and member 85 are operated by the treadle 74 and strut 44 coincidentally with the operation of the flushing mechanism by reason of the connection 43 between the strut 44 and the link 137 at the lever 50. Therefore, the same upward thrust of the strut 44 causes the connecting link 50 137 to rotate the lever disc 125 in a direction whereby the lever 124 exerts a force on the crank arm 120 by means of the slot and lug 122 and 55 123, respectively, to move the member 85 into sealing relation with opening 90 as shown in Fig. 3. During this initial movement, the pan 75 has not moved from its closed position in sealing relation with the discharge opening 80; but the stud 140, on the disc 125, has approached the crank arm 141 on the dump pan shaft 81 to a 60 position where contact is made immediately after the member 85 reaches closed position. As shown in Fig. 3, it will be seen that both the dump pan 75 and bottom closure member 85 are in fully closed position, while contact with the crank arm 70 141 has not yet been made by the stud 140; but

the lever 124 is still in engagement with the lug 135. When the engagement between the lug 140 and the crank arm 141 occurs, a positive direct connection between the treadle mechanism and shaft 81 is made, thereby to dump the pan 75.

Contact between the lever 124 and lug 135 is maintained during the initial movement by spring 127 up to that point in the operation when the member 85 contacts the chute 17, thus acting rigidly to close the bottom closure member, and when that point is reached the lug 135 moves away from lever 124 as the stud 140 contacts the crank arm 141 to dump the pan 75 upon continued rotation of the disc 125, thus acting flexibly to afford the continued movement to open the dump pan. During such continued rotation, the lever 124 remains in its final position of movement in closing the member 85, while the spring 127 compensates for the relative rotation between the parts 124 and 125; and the tension thereon is gradually increased as the disc turns the crank arm 141 by means of the stud 140 to rotate the shaft 81 and thereby dump the pan 75, as shown in Fig. 4. The final dumping position of the pan 75 is illustrated in Fig. 4, at which time the pan enters recess 18 in the rear wall of chute 17 while the bottom closure member 85 remains in sealing relation to chute opening 90. In this figure, it will be noted that the lever 124 is still in its final position of movement, while the disc 125 has rotated to its final position with the lug 135 spaced from the lever 124 and the stud 140 bearing against the crank arm 141 in the final position of that member with the spring 127 wound up to its greatest degree of tension under normal conditions. Treadle 74 has moved to its extreme position with the bumper 40 bearing against the floor, and the flushing mechanism has attained its full flushing force—sending water through the nozzles 69 and 70 into the bowl 26 to be drained through discharge opening 80 into the chute chamber 17, after which all of the operating parts are restored to their normal position in directly reverse sequence with the pan 75 first closing completely before the bottom closure member 85 is opened to release the contents from the chute 17 through opening 90, at which time the parts have again assumed the position shown in Fig. 2.

While the dumping operation of the pan 75 and the initial operation of the bottom closure member 85 takes place coincidentally with the operation of the flushing mechanism, the release of each mechanism is accomplished independently of the other; and the speed with which the flushing mechanism returns to non-flushing condition is not dependent upon or affected by the time required for the dump pan and bottom closure member operating parts to return to normal position after the pressure has been released from treadle 74. By means of slot 143 in the link 137 at the connection to lug 136 on the disc 125 in combination with the floating type mounting of the lever disc 125, the flushing mechanism is adapted to return to non-flushing condition even though the operating parts for the pan 75 and member 85 might, for some reason, be prevented from returning to their normal position of rest, whereby continuous operation of the flushing valve and consequent draining of the water supply tank (not shown) is prevented. It will be seen that by reason of the floating connection of the disc 125, that member, after having been operated to its extreme position of movement to dump the pan 75, will return at

least to a position where the lug 135 will bear against lever 124 under the influence of spring 127; and in the event that the member 85 for some reason is prevented from opening, that position will be as shown in Fig. 3 with the lever 124 prevented from returning fully to its normal position of rest by the crank arm 120. With the disc 125 having reached this position, the flushing mechanism then may return to fully released, non-flushing position by reason of the slotted engagement 143 of the connecting link 137 with the lug 136 on the disc. Even though both the bottom closure member 85 and the dump pan 75 be prevented from returning to their respective normal positions—i. e., the member 85 prevented from opening and the pan 75 prevented from closing, the flushing mechanism will be released as above described. By having the floating type mounting of the lever and disc mechanism 124 and 125 and the loose connection between the stud 140 and crank arm 141, the dump pan 75 may remain in any position, because of an obstruction, without affecting the return of the flushing mechanism to released position. The pan 75 may be pressed open with a hose or the like for cleaning purposes, against the resistance offered by spring 88, without operating either the bottom closure member 85 or the flushing mechanism; and, likewise, the bottom closure member 85 may be swung through its complete arc of travel without affecting either the pan 75 or the flushing mechanism. In the event the bottom closure member 85 should become obstructed and fail to close, the compensating action of spring 127 will still permit dumping of the pan 75 and operation of the flushing mechanism.

In the modified type of arrangement illustrated in Figs. 14, 15 and 16, the mechanism, in so far as the operation of the dumping pan 75 is concerned, is exactly the same as that heretofore described and therefore will require no further description; but the counterbalancing of the bottom closure member 85 is accomplished by means of a torsional spring without the use of weights. That end of the one stub shaft 102 upon which the counterweight 106 was mounted is now disposed flush with the end of bearing 103 and provided with a slotted cap screw 155 threaded into the end of the shaft and having a finished head to the diameter of the bearing 103. At the opposite side of the base 11 on the other stub shaft 102, a combined crank arm and spring housing member 156 is substituted for the crank arm 120 of the previously described embodiment. The crank arm is provided with a slot 157 for cooperation with the lug 123 on the actuating lever 124 and is anchored to the stub shaft 102 by means of set screw 121 entered through hub 158. The crank arm is provided with an integral, cylindrical spring housing 159 containing a torsional spring 160 anchored at its outer extremity to the perimeter of the housing by means of rebent flange 161 entered in slot 162. The spring 160 is coiled about fixed bearing member 163 for the stub shaft 102, which is secured in the base 11, like bearing 103, by means of similar nuts 104 and is anchored thereto, at its inner end, by means of flange 164 entered in groove 165.

By the direction of the spring coils, it will be noted that the spring 160 exerts a force between the fixed bearing 163 and the spring housing 159 tending to rotate the crank arm 156 and the shaft 102 in a direction to open the bottom clo-

sure member 85, and a stop 166, integral with the housing 159 and adapted to bear on the base flange 12, is provided to limit the opening movement. A similar integral stop 167 is disposed on the diametrically opposite side of the housing 159 in order to permit use of the member in reverse with mechanism on the opposite side of the closet stand without change in the casting. Contact with the chute 11 by the member 85 serves as a positive stop to prevent further movement of the member 159. The sole function of the spring 160, normally, is to open the bottom closure member 85; but it of course offers additional compensating action, supplementing the spring 127, in the event the bottom closure member 85 fails to operate. The spring housing 159 is closed at the side adjacent to the base 11 by means of a washer 168 seated against collar 169 on the bearing 163. In operation, the spring 160 is maintained under less tension than the spring 127, whereby the resistance offered thereby to the closing of the member 85 may be overcome without causing the lug 135 to break contact with the lever 124 before the stop 167 strikes the base flange 12 as the mechanism is actuated. The arrangement functions in exactly the same sequence as that previously described, with bottom member 85 closing first—the spring 160 being wound to a greater degree of tension in accomplishing this; then the spring 127 is wound to a greater degree of tension as the pan 75 is dumped and in reverse sequence as the mechanism is released.

The parts of the operating mechanism are designed for use, in either right or left hand mechanisms—thus eliminating the need for extra castings; and it will be seen that by the mere reversal of the lug 136 on plate 125 all of the parts may be reversed and used either right or left for assembly on either side of the closet stand. In actual practice, the disk 125 is made with two of the lugs 136, one disposed upon each side of the vertical line which passes through the center of the stop 135—the lug 140 and the central opening forming the bearing therefor, whereby the member may be reversed for use on either side of the stand by merely turning it around.

It is to be noted that while the springs 88 and 127 are wound up simultaneously in the operation of the pan 75, they do not act in opposition one to the other but operate separately—each performing its own function independently of the other, but the springs 127 and 160 do function in opposition in that spring 160 resists closing of the member 85, with the spring 127 necessarily overcoming the spring 160 as the lever 124 moves the crank arm 156 to a position closing member 85 without the contact between lug 135 and lever 124 being broken until the stop 167 strikes base flange 12.

From the foregoing, it will be seen that there has been provided a lightweight water closet construction with a lightweight operating mechanism in which all unnecessary weights have been eliminated and in which compensating action is provided for all possible conditions adversely affecting the operation of the mechanism, whereby the flushing mechanism is rendered operative at all times.

What is claimed is:

1. In a water closet including a bowl having a discharge opening and a supporting stand having a drain opening with a dump pan and a closure member for the discharge and drain open-

ings, respectively, and each having an operating shaft; means for operating said dump pan and closure member, including a lever assembly floatingly mounted on the pan operating shaft, said assembly comprising relatively movable members connected by a spring, and means on the closure member shaft co-operating with the lever.

2. In a water closet including a bowl having a discharge opening and a supporting stand having a drain opening with a dump pan and a closure member for the discharge and drain openings, respectively, and each having an operating shaft; means for operating said dump pan and closure member, including a lever assembly mounted on the pan operating shaft, said assembly comprising a lever arm and an actuating member each mounted for movement relative to said operating shaft and to the other, and means on the closure member shaft co-operating with said lever arm.

3. In a water closet including a bowl having a discharge opening and a supporting stand having a drain opening with a dump pan and a closure member for the discharge and drain openings, respectively, and each having an operating shaft; means for operating said dump pan and closure member, including a lever assembly mounted on the pan operating shaft, said assembly comprising a lever arm and an actuating member each mounted for movement relative to said operating shaft and to the other, a torsional spring connecting said lever arm and actuating member and resisting relative movement thereof, and means on the closure member shaft co-operating with said lever arm.

4. In a water closet including a bowl having a discharge opening and a supporting stand having a drain opening with a dump pan and a closure member for the discharge and drain openings, respectively, and each having an operating shaft; means for operating said dump pan and closure member, including a lever assembly mounted on the pan operating shaft, said assembly comprising a lever arm and an actuating member each mounted for movement relative to said operating shaft and to the other, a spring connecting said lever arm and actuating member and resisting relative movement thereof, and means on the closure member shaft co-operating with said lever arm.

5. In a water closet including a bowl having a discharge opening and a supporting stand having a drain opening with a dump pan and a closure member for the discharge and drain openings, respectively, and each having an operating shaft; means for operating said dump pan and closure member, including a lever assembly mounted on the pan operating shaft, said assembly comprising a lever arm and an actuating member each mounted for movement relative to said operating shaft and to the other, a torsional spring connecting said lever arm and actuating member and resisting relative movement thereof, a crank arm on the pan operating shaft, means on said actuating member engageable with said crank arm, and means on the closure member shaft engageable with said lever arm.

6. In a water closet including a bowl having a discharge opening and a supporting stand having a drain opening with a dump pan and a closure member for the discharge and drain openings, respectively, and each having an operating shaft; means for operating said dump pan and closure member, including a lever assembly mounted on the pan operating shaft, said as-

sembly comprising a lever arm and an actuating member each mounted for movement relative to said operating shaft and to the other, a torsional spring connecting said lever arm and actuating member and resisting relative movement thereof, stop means on the actuating member engageable with the lever arm, a crank arm on the pan operating shaft, means on said actuating member engageable with said crank arm, and means on the closure member shaft engageable with said lever arm.

7. In a water closet including a bowl having a discharge opening and a supporting stand having a drain opening with a dump pan and a closure member for the discharge and drain openings, respectively, and each having an operating shaft; flushing mechanism, means for operating said dump pan and closure member, including a lever assembly mounted on the pan operating shaft, said assembly comprising a lever arm and an actuating member each mounted for movement relative to said operating shaft and to the other, a torsional spring connecting said lever arm and actuating member and resisting relative movement thereof, stop means on the actuating member engageable with the lever arm, a crank arm on the pan operating shaft, means on said actuating member engageable with said crank arm, means on the closure member shaft engageable with said lever arm, a lost motion connection between the actuating member and said flushing mechanism, and means for actuating said flushing mechanism simultaneously with the operation of said dump pan and closure member.

8. In a water closet including a bowl having a discharge opening and a supporting stand having a drain opening with a dump pan and a closure member for the discharge and drain openings, respectively, and each having an operating shaft; counterbalancing means for the closure member, a torsional spring anchored to the supporting stand and connected to the dump pan operating shaft to balance said dump pan, means for operating the dump pan and closure member including a lever assembly mounted on the pan operating shaft, said assembly comprising a lever arm and an actuating member each mounted for movement relative to said operating shaft and to the other, a torsional spring connecting said lever arm and actuating member and resisting relative movement thereof, stop means on the actuating member engageable with the lever arm, a crank arm on the pan operating shaft, means on said actuating member engageable with said crank arm, and means on the closure member shaft engageable with said lever arm.

9. In a water closet including a bowl having a discharge opening and a supporting stand having a drain opening with a dump pan and a closure member for the discharge and drain openings, respectively, and each having an operating shaft; counterbalancing means for the dump pan, a torsional spring anchored to the supporting stand and connected to the closure member operating shaft for balancing that member, means for operating the dump pan and closure member including a lever assembly mounted on the pan operating shaft, said assembly comprising a lever arm and an actuating member each mounted for movement relative to said operating shaft and to the other, a torsional spring connecting said lever arm and actuating member and resisting relative movement thereof, stop means on the actuating member engageable with the lever arm,

75 a crank arm on the pan operating shaft, means on said actuating member engageable with said crank arm, and means on the closure member shaft engageable with said lever arm.

5 10. In a water closet including a bowl having a discharge opening and a supporting stand having a drain opening, a dump pan for the discharge opening having an operating shaft, a closure member for the drain opening having an operating shaft, a torsional spring coiled around the operating shaft for the closure member having one end anchored with respect to the supporting stand and having its other end anchored with respect to the last-named shaft for counterbalancing said closure member, a housing enclosing said spring, mechanism connecting the shafts for sequential rotation thereof, and means for actuating said mechanism.

20 11. In a water closet having stationary members comprising a bowl and a supporting stand provided respectively with an upper opening and a lower opening a closure member for each opening and an operating shaft mounting each closure member, a torsional spring coiled around 25 one of said shafts having one end anchored with respect to one of said stationary members and its other end anchored relatively to said last-named shaft for counterbalancing the closure member mounted by said shaft, a housing enclosing said spring, mechanism connecting the shafts for sequential rotation thereof, and means for actuating said mechanism.

30 12. In a water closet having a supporting stand and a bowl and having upper and lower openings, a dump pan for the upper opening and a closure member for the lower opening, upper and lower operating shafts for the dump pan and closure member, respectively, operatively mounted in the supporting stand, means for operating said shafts to actuate the dump pan and closure member comprising an assembly floatingly mounted on the upper shaft and having a lever, a crank fixedly mounted on the lower shaft, said lever cooperating with said crank to actuate the closure member prior to the dump pan, a crank fixedly mounted on the upper shaft cooperating with the assembly to actuate the dump pan, and means for actuating said assembly.

35 13. In a water closet having an upper dump pan and a lower closure member, upper and lower operating shafts for the dump pan and the closure member respectively, means for operating said shafts to actuate the dump pan and closure member comprising an assembly floatingly mounted on one of the shafts and having a lever, a crank fixedly mounted on the other shaft for operation thereof and cooperating with the lever, and a crank fixedly mounted on said one shaft cooperating with said assembly, and means for actuating said assembly.

40 14. In a water closet including a bowl having a discharge opening and a supporting stand having a drain opening, a dump pan for the discharge opening having an operating shaft, a flat spiral torsional spring coiled around said shaft for counterbalancing said pan, anchorage means for said spring fixed with relation to the supporting stand and extending adjacent to said shaft, a housing fixed on said shaft and enclosing said spring, the end of the radially innermost coil of the spring being anchored to said means and the end of the radially outermost coil of the spring being anchored to said housing, and means for actuating said pan.

45 75 CLARENCE H. JOHNSON.
